2,447,526

COMBINED DOOR HOLDER AND BURGLAR
ALARM

James E. Clivis, Glendale, Calif.

Application March 30, 1946, Serial No. 658,454

8 Claims. (Cl. 116—91)

1

This invention relates to a combined door holder and burglar alarm.

More specifically speaking the invention pertains to a type of audible door-operable alarm wherein the casing which contains the alarm is mounted upon a swingable door, which door may be set in a more or less open position but which, when opened from certain set positions sufficiently to admit a person through the door opening, will cause the alarm to sound.

It is an object of the invention to provide a simplified combination of mounting means and actuating means for the alarm proper which means can be conveniently mounted over the door opening and upon the free edge portion of a door of a building.

Another object is to provide an improved door holder arm which has a novel and more advantageous arrangement of door-setting shoulders and which is more conveniently adjustable to and from an inoperative position.

Still another object is to provide an improved means for setting and holding a door in a slightly open position to secure better ventilation, while at the same time preventing unauthorized persons from passing through the door opening without sounding an alarm.

Other objects, advantages and features of invention will hereinafter appear.

Referring to the accompanying drawing which illustrates a preferred embodiment of the invention,

Fig. 1 is a fragmental perspective view showing the device in a position wherein the alarm is sounding by reason of an opening movement having been given to the door beyond that for which the door was set; the alarm ceasing to sound if the door is closed.

Fig. 2 is a fragmental, vertical sectional view of the door holder mounting mechanism.

Fig. 3 is a reproduction of a portion of Fig. 1 showing the parts differently adjusted.

Fig. 4 is a view of the outer end portion of the door holder arm showing said arm adjusted to a still different position wherein it holds the door ajar for ventilation but is in an inoperative relation to the alarm.

Fig. 5 is a fragmental side elevation showing the door holder swung to its inoperative position.

Referring in detail to the drawing, the door 7 is shown hinged to one of the vertical side portions of a door frame 8, a bracket consisting of a strap metal clip 9 being fastened to said door frame above the door opening 10 adjacent to that side of said door opening that is farthest from

2

the hinged edge of the door. To said bracket is anchored one end of a door holding arm 11 which can be tilted vertically and swung laterally. The free or outer end portion of said arm cooperates with an alarm actuating means 12 in an operative relation to the alarm proper 13, said means 12 and alarm 13 both being secured to the part of the outer face of the door which is adjacent to the door's free edge.

10 The alarm proper is furnished with an upwardly projecting sleeve 14 within which operates a spring-pressed headed plunger 15 normally maintained by its spring at the upward limit of its travel so that the alarm does not sound unless said plunger is depressed against the opposition of its spring. An alarm actuating lever 16 normally rests lightly upon the upper, headed end of the aforesaid plunger 15, not pressing thereagainst with sufficient force to set off the alarm. One end of said lever 16 is pivoted at 16a with a working fit in a channel shaped ear 17 carried by a rectangularly U-shaped upper part 18 of a bracket plate or apron 19, this bracket plate being attached to the outer face 25 of the door by any suitable means, for example by screws 20, and its lower part providing also a mounting means for the alarm proper 13. It will be seen that the mounting arms for the lever 16 are integral with the upper corner portions 30 of the bracket plate 19.

Adjacent to the free edge of the upper part of the door the part 18 has an outwardly directed arm 21 furnished at its outer end with an upwardly directed finger 22 immediately behind which there is a deep notch 23 in the upper edge of the arm 21. The outer side of the finger 22 has formed upon it an upper shoulder 24 and a lower shoulder 25, these shoulders facing downwardly.

40 The lower edge of the strap iron of which the door holding arm is shown as being constructed is provided in its free end portion with certain rest portions and locking shoulders, there being at the outer end of the arm a rest surface 28 inwardly from which extends an upward bevel 29. At the inner end of this bevel there is an inwardly facing stop shoulder 30 inwardly beyond which are the door rest surfaces 31 and 32, there being a bevel 33 between the latter two rest surfaces and a bevel 34 at the inner end of the rest surface 32. As to the rest 32 it may be described as a broad notch having a widening bevel at each end, this notch thus being adapted to overlie an intact portion 35 of a rest plate 36 secured flatwise to the outer part of the top surface of the

3

free edge portion of the door 7, said rest plate having through it an aperture 37 sufficient to unobstruct the downswing of the arm 11 (inclined downwardly at such times) to allow the rest surface 32 of said arm to seat upon said

4

ly its free end, and an alarm mounted on said door frame, and actuating mechanism for said alarm mounted on the door and operatively related to the free end portion of said arm at times to be put into operation thereby, parts of said

channel shaped clip mounted on a door frame superjacent to a door opening, the open side of said channel shaped clip being directed outwardly from the door frame, the upper side of said clip terminating in a downwardly directed lip having a central notch and an inclined edge at each side of said notch, a door holding arm having an anchored end portion pivoted to said clip within its channel portion to swing both horizontally and vertically, and a spring connected with the attaching means for said door holding arm and at times holding a part of said arm within the aforesaid notch to prevent the arm from being horizontally swung, the outer part of said arm having shoulder means engageable with the upper edge of a door to prevent outswing of the latter, said arm being manually depressible out of said notch preparatory to swing the arm horizontally to an inoperative position in relation to the door.

7. A combined means for mounting and actuating an alarm comprising a bracket plate or apron attached with one of its faces abutted in a flatwise manner against a door and supporting adjacent to its opposite face an alarm having an upwardly projecting plunger for its operation, said apron carrying two outwardly extending arms one at each side of said plunger, a lever pivoted to one of said arms and guided in vertical swinging by the other of said arms, said lever normally resting upon the upper end of said plunger with insufficient pressure to set off the alarm, and an arm having an inner end portion mounted superjacent to the door opening and an outer end portion positionable to depress said lever when brought into contact therewith by outswinging of the door.

8. In a construction of the kind described, a

clip mounted on a door frame superjacent to the door opening and adjacent to that side of a door opening which is farthest from the hinges of the door, a door holder arm having an anchored end 5 connected to said clip and a free end portion adjustable to and from a holding relation to the upper edge portion of said door, means yieldingly acting upon said arm and tending to swing downwardly its free end, an alarm mounted on said 10 door, an actuating mechanism for said alarm mounted on the door and operatively related to the free end portion of said arm at times to be put into operation thereby, said arm having a notch in its lower side in a considerably spaced relation 15 to its outer end to fit over a part of the upper edge of the door to hold the door at a definite outswung position, said notch having a beveled outer end thus allowing a wider forcing open of the door, and an alarm actuating means carried by 20 the door and acted upon by said arm when such wider forcing open of the door occurs.
